UNITED STATES PATENT OFFICE

WALTER B. CLIFFORD, OF CAMBRIDGE, MASSACHUSETTS

METHOD OF FORMING BELLows TUBING

Application filed September 19, 1928. Serial No. 307,036.

The present invention relates to a method of forming bellows tubing and more particularly to such a method adapted to be employed in conjunction with the forming machine disclosed in my Patent No. 1,689,620, granted October 30, 1928. The present invention is a continuation in part of that disclosed and claimed in my earlier application Serial No. 221,570, filed September 23, 1927.

According to the present invention, the tube is first sealed at opposite ends with an opening or passage provided in one end for the introduction of fluid pressure during the forming operation. The end fitting provided with the fluid pressure passage projects slightly beyond the outer diameter of the tube to provide a shoulder for engagement during the forming operation. In certain cases the tube may be provided with a fitting upon both ends and in other cases the tube may be left in its initial cupped form and sealed with a fitting only at the open end. In either case, however, this method of procedure has decided advantages due in part to the fact that the joint formed between the fitting and the tube end is automatically tested by the high pressures employed during the forming operation, and in part to the fact that the operation of sealing the end of the tube is much simplified by applying the fitting to the plain tube before formation of the bellows folds rather than thereafter.

In the drawings illustrating the various steps carrying out the present invention,

Fig. 1 represents a thin wall cupped tube;

Fig. 2, a tube with the closed end removed;

Fig. 3, the same tube with the ends flanged outwardly for the reception of a fitting;

Fig. 4, the same tube with the fitting introduced and the outturned end spun inwardly over the fitting; in each of the preceding views the tube is broken midway of its ends to economize in space, and the thickness of the tube is exaggerated;

Fig. 5 illustrates the fitting hermetically sealed to the tube end with a soldered joint;

Fig. 6, the completed assembly after the formation of the bellows folds;

Fig. 7 represents a similar cupped tube to

that shown in Fig. 1, but of somewhat different dimensions;

Fig. 8, the same tube with the cupped end shaped to receive a valve;

Fig. 9, the valve locked in place within the cupped end;

Fig. 10, the outward spinning and assembly with an end fitting; in each of the preceding Figures 7 to 10 inclusive, the tube is broken away intermediate its ends, and for purposes of illustration the thickness is shown somewhat exaggerated;

Fig. 11, the complete tube assembly prior to forming; and

Fig. 12, the completed bellows assembly with the thickness of the bellows wall exaggerated for purpose of illustration.

Referring to the illustrated embodiment of the invention, a cupped tube is indicated at 20. This tube may be drawn in the usual manner to the desired dimensions and with a grained size and temper properly suited for the work which it must undergo in the formation of the bellows folds. After the completion of the cupped drawn tube which may approximate one inch in diameter with a length of ten inches and a wall thickness of seven-thousandths of an inch, the closed end is removed as indicated in Fig. 2, and thereafter the opposite ends of the tube are spun outwardly at 22 and 23 to form an annular offset portion, as indicated in Fig. 3. This spinning may be accomplished through the employment of a spinning roll indicated at 24, which is moved transversely of the axis of the tube during a relative rotation of the tube and roll. The annular enlargement upon opposite ends of the tube is designed for the reception of an end fitting 26 which is somewhat larger in diameter than the external diameter of the tube but is received within the annular enlargement, seating against the shoulder formed thereon. This end fitting, as indicated in Fig. 4, may comprise a ribbed disk 28 having a hollow stud 30 riveted centrally therein, as indicated. The fitting at the opposite end may be provided with a larger stud 32. After assembly of the head or disk within the outer enlarged end of the tube, the latter is spun inwardly at 34 and

the head is thereafter sealed by solder 36 which serves not only to seal the annular joint between the edge of the disk and the tube end, but also the joint between the disk and stud 5 30, the annular rib 38 formed intermediate the disk serving to promote the flow of solder toward the two joints. After completion of the tube assembly, as shown in Fig. 5, the stud 32 being closed to hermetically seal one 10 end of the tube, the assembly is mounted with- in a forming machine of the type disclosed in the patent referred to, with the end forming plates 40 located behind the shoulder 42, and the tube contracted into a series of bel- 15 lows folds to produce the bellows indicated at 44 in Fig. 6.

In the method as outlined in Figs. 7 to 12 inclusive, a tube 50 is first shaped at the closed end to form the stepped indentation 52. Co- 20 operating with this stepped indentation is a valve member 54 having a more or less resili- ent locking portion 56 projecting from the bottom which is adapted to be forced into the lowest portion 58 of the indentation 52 25 and upon pressure being applied, spread outwardly, as shown in Fig. 9, to lock the portion 56 rigidly within the lowermost recess 58. Thereafter the joint may be sealed with solder as indicated at 60. Subsequent to the 30 application of the valve to the closed end of the tube, the open end is spun outwardly at 62 for the reception of a head 64 which is indicated as provided with a threaded stud 66 and a projecting ring 68 adapted for the 35 reception of a tube 70 which acts as a stop to limit the movement of the bellows in col- lapsed position. As shown more particularly in Fig. 11, the stop tube is assembled with the head 64 and is located in assembled posi- 40 tion by spinning or flanging the ring 68 out- wardly at 72. Thereafter the head and stop assembly is inserted in the portion 62 of the tube which is then turned inwardly at 74 and soldered at 76 to hermetically seal the tube 45 except for the provision of the fluid passage 78. Thereafter the completed bellows assem- bly 80 is formed in the machine as previously described.

It will be evident that in this alternative 50 mode of procedure only one end of the tube is left open for closure with an end fitting. Obviously, if no fitting was desired at the closed end of the tube, it would be essential only to apply a single end fitting to the open 55 end, thus eliminating the necessity of one end fitting and the joint created thereby.

With this method, the end fitting in each 60 case is applied prior to the formation of the bellows, and during such formation the rela- tively high fluid pressure employed serves as a means for automatically testing not only the tube structure itself, but the strength and tightness of the joint between the end of the tube and the fitting. Inasmuch as the pres- 65 sures ordinarily employed are on the order of

500 pounds per square inch and upwards, it will be evident that an improperly jointed end fitting will cause failure of pressure and failure of the forming operation, as well as a weak or porous tube structure.

70

Not only does such a method permit testing of the end joint during the formation of the bellows and simplify the application of the end fitting due to its application to the plain tube, but in addition, this method permits 75 the employment of an end fitting having a diameter on the order of the initial tube rather than the outer diameter of the finished bellows. This is important not only because it reduces the length of the circumferential 80 joint, but also because a smaller and lighter fitting may be employed. In many uses for devices of this character, especially where ex- 85 treme sensitivity is required, the weight of the bellows structure is governed to a sub- stantial extent by the character and size of the end fitting. In usual practice, where the end fittings are applied after the formation of the bellows folds, it has not been the usual 90 custom to employ end fittings substantially smaller than the diameter of the outer con- volution, the fittings as a rule being mounted upon and secured to the last convolution in a manner which will be obvious to those skilled 95 in the art.

What is claimed is:

1. The method of making bellows tubing which consists in forming a thin-wall tubular shell working the wall of the shell outwardly at an open end to form an enlarged annular 100 portion, assembling an end fitting with a pas- sage formed therein within the enlarged annular portion, sealing the end fitting to the tubular shell, and forming a series of bellows folds in the shell through the employment of 105 internal fluid pressure introduced through the passage in the end fitting.

2. The method of making bellows tubing which consists in forming a thin-wall tubular shell, working the wall of the shell outwardly 110 at an open end to form an enlarged annular portion, assembling an end fitting with a pas- sage formed therein within the enlarged annular portion, turning the peripheral edge of the annular portion inwardly over the cor- 115 responding edge of the end fitting, hermetically sealing the fitting to the tubular shell, and forming a series of bellows folds sub- stantially larger at the outer convolutions than the diameter of the end fitting through 120 the employment of fluid pressure introduced internally through the passage in the end fitting.

3. The method of making bellows tubing which consists in forming a thin-wall tubu- 125 lar shell, working the wall of the shell out- wardly at an open end to form an enlarged annular portion, assembling an end fitting with a passage formed therein within the enlarged annular portion, sealing the end 130

fitting to the enlarged annular portion, and introducing fluid pressure internally through the passage in the end fitting while maintaining the end fitting in sealing engagement 5 with a pressure source by rigidly supporting the shoulder formed by the enlarged annular portion.

4. The method of making bellows tubing which consist in forming a recessed portion in the closed end of a thin-wall tubular shell, 10 assembling a fitting having an expansible locking portion in the previously formed recess in the closed end, and expanding the locking portion of the fitting to lock the latter 15 firmly within the recessed portion of the shell.

5. The method of making bellows tubing which consists in forming a recessed portion in the closed end of a thin-wall tubular shell, 20 assembling a fitting having an expansible locking portion in the previously formed recess in the closed end, expanding the locking portion of the fitting to lock the latter firmly within the recessed portion of the shell, closing 25 the opposite open end of the shell with a fitting having a fluid passage extending therethrough, and forming bellows folds through the employment of internal fluid pressure introduced through the passage in 30 the end fitting.

6. The method of producing bellows folds with an interior stop, which consists in assembling and connecting a head and an interior stop, next mounting and connecting 35 the assembled head and stop in a thin-wall tube, and finally forming bellows folds in the tube by fluid pressure introduced therein through one end of the tube.

7. The method of making bellows tubing 40 which comprises forming a peripheral shoulder adjacent an open end of a thin-wall tube for receiving and locating an end fitting, assembling an end fitting having a head seated against the shoulder and a fluid passage 45 extending therethrough, sealing the end fitting to the tube, and introducing fluid pressure into the tube through the passage in the end fitting while maintaining the fitting in sealing engagement with a pressure source by a support engaged behind the 50 shouldered portion of the tube.

8. The method of making bellows tubing which comprises forming a peripheral shoulder adjacent an open end of a tube for 55 receiving and locating an end fitting, the tube being provided with an annular portion beyond the shoulder, assembling an end fitting having a head with the head received within the annular portion and seated against the 60 shoulder, and sealing the fitting to the tube wall.

9. The method of making bellows tubing which comprises forming a peripheral shoulder adjacent an open end of a tube for 65 receiving and locating an end fitting, the

tube being provided with an annular portion beyond the shoulder, assembling an end fitting having a head with the head received within the annular portion and seated against the shoulder, spinning the annular portion 70 over the head when in assembled position, and sealing the fitting to the wall of the tube.
